LLP; Jeffrey Standley; Jeffrey Norris(57) **CLAIM**

The ornamental design for a trim component, as shown and described.

DESCRIPTION

FIG. 1 is an end elevation view of a trim component showing our new design.

FIG. 2 is a perspective view of the trim component of FIG. 1.

FIG. 3 is a front elevation view of the trim component of FIG. 1.

FIG. 4 is a bottom plan view of the trim component of FIG. 1.

FIG. 5 is a top plan view of the trim component of FIG. 1.
FIG. 6 is a perspective view of the trim component of FIG. 1; and,

FIG. 7 is a rear elevation view of the trim component of FIG. 1.

The trim component is shown with a symbolic break along its length. The appearance of any portion of the trim component between the break lines forms no part of the claimed design.

The broken lines shown in FIGS. 1 through 7 illustrate portions of the trim component that form no part of the claimed design.

Primary Examiner — Llorellys Martinez(74) *Attorney, Agent, or Firm* — Standley Law Group
LLP; Jeffrey Standley; Jeffrey Norris(57) **CLAIM**

The ornamental design for a trim component, as shown and described.

DESCRIPTION

FIG. 1 is an end elevation view of a trim component showing our new design.

FIG. 2 is a perspective view of the trim component of FIG. 1.

FIG. 3 is a front elevation view of the trim component of FIG. 1.

FIG. 4 is a bottom plan view of the trim component of FIG. 1.

FIG. 5 is a top plan view of the trim component of FIG. 1.

FIG. 6 is a perspective view of the trim component of FIG. 1; and,

FIG. 7 is a rear elevation view of the trim component of FIG. 1.

The trim component is shown with a symbolic break along its length. The appearance of any portion of the trim component between the break lines forms no part of the claimed design.

The broken lines shown in FIGS. 1 through 7 illustrate portions of the trim component that form no part of the claimed design.
